[57] CLAIM

The ornamental design for a material machining device
enclosure, as shown and described.

DESCRIPTION

FIG. 1 is a perspective view showing a first preferred

embodiment of my design for a material machining
device enclosure;FIG. 2 is a front elevation view of the embodiment of
FIG. 1;FIG. 3 is an end elevation view of the embodiment of
FIG. 1, it being understood that the end opposite that
shown is the same;FIG. 4 is a top plan view of the embodiment of FIG. 1;
FIG. 5 is a bottom plan view of the embodiment of FIG.
1;FIG. 6 is a rear elevation view of the embodiment of
FIG. 1;FIG. 7 is a front elevation view of a second preferred
embodiment of my design for a material machining
device enclosure, it being understood that all other
views of such design are the same as the corresponding
views of my first preferred embodiment shown in
FIGS. 1-6;FIG. 8 is a front elevation view of a third preferred
embodiment of my design for a material machining
device enclosure;FIG. 9 is a top plan view of the third preferred embodiment
of my design;FIG. 10 is a rear elevation view of the third preferred
embodiment of my design; andFIG. 11 is a bottom plan view of the third preferred
embodiment of my design, it being understood that both
end elevation views of such embodiment are the same as
the end elevation view depicted in FIG. 3 for the first
preferred embodiment of my design.FIG. 1
